UNITED STATES PATENT OFFICE.

SYLVESTER C. GARDNER, OF SWANSEA, AND CLARK CHASE, OF FALL RIVER, MASSACHUSETTS, AND CHARLES V. KENT, OF BANGOR, PENNSYLVANIA.

CARRIER.

960,534.

Specification of Letters Patent. Patented June 7, 1910.

Application filed May 12, 1908, Serial No. 432,554. Renewed March 19, 1910. Serial No. 550,515.

To all whom it may concern:

Be it known that we, SYLVESTER C. GARDNER, CLARK CHASE, and CHARLES V. KENT, all citizens of the United States, residing, 5 respectively, at Swansea, in the county of Bristol and Commonwealth of Massachusetts, at Fall River, in said county and Commonwealth, and at Bangor, in the county of Northampton and State of Pennsylvania, 10 have jointly invented a certain new and useful Improvement in Carriers, of which the following is a specification, reference being had therein to the accompanying drawings.

Our invention relates to carriers, in which 15 the weight of the load borne by the carrier, is employed in locking and unlocking the carrier to and from its support, upon which the carrier is designed to travel.

It has been found that with some of the 20 carriers of the above class, if, while the load is sustained above its seat, but not in it, the carrier becomes unlocked from its support, the operator loses control of the carrier, which, in spite of the operator, and through 25 the action of the weight of the load, moves along its support with a speed sufficient to permit the load to descend or "drop" into its seat, sometimes with objectionable force.

Now one of the principal objects of our 30 invention is to provide such a carrier, with means whereby the carrier remains locked to its support until the load has found its seat in the carrier. And we attain this object by providing a movable seat for the load, so 35 connected with gripping mechanism of the carrier, that the latter remains in locking engagement with the support, until the load by engaging its seat, moves the seat and connected parts, and causes the gripping 40 mechanism to disengage the support. In other words, the operator always has control of the load, and there can be no "drop."

A further object of our invention is to 45 provide means whereby the movements of the load are utilized to control the movements of the seat, into and out of the path of the load, to enable the load to become fastened to, and unfastened from, the carrier. And we attain this object by so connecting 50 the seat to the gripping mechanism, and by so designing the seat and the releasing apparatus, that while the gripping mechanism is holding the carriage locked to its support, the seat may be controlled by the moving load, and be moved into and out of the

path of the load, for the purpose of confining the load to, and permitting it to escape from, the carrier.

In the drawings illustrating the principle of our invention, and the best mode now known to us of applying that principle, Figure 1 shows a carrier, and a grab-bucket. Figs. 2 and 3 are end elevations, showing the carrier, and only the head of the bail of the bucket. Figs. 4, 5, 6 and 7 show the carrier with its front plate and gripping jaw removed, to disclose, in various successive positions, the coöperating parts controlled by the upward and the downward movements of the head of the bucket; Figs. 4 and 5 illustrate the changes due to the upward movement; the releasing tongue, connecting parts, and spring being omitted for the sake of clearness; while Figs. 6 and 7 make plain what takes place because of the downward movement of the load, to release the bucket from the carrier. Fig. 8 shows a modified form adapted for use in connection with a load which, unlike a grab-bucket, is not to be dumped, and does not require the use of a second, or opening fall.

A support or trolley rope or cable A, Figs. 1, 2, 3, has, movably mounted thereon, a carrier B which sustains a load C, here shown in the form of a grab-bucket.

For the sake of simplicity and economy the carrier is, as far as possible throughout, made up of counterpart construction; that is, each part is made up of united duplicates. The carrier B has a skeleton frame, 90 the front D and the back E of which consist of parallel members, and have, mounted between them, trolley wheels F, and other coöperating parts, to be fully described later. As the front D and the back E are 95 symmetrical, only one, as D, will be described in detail. A trolley wheel plate a, having bearings therein for trolley wheels F, has depending therefrom, and at right angles thereto, four other plates b, c, d, e, 100 two of which c, d, are centrally located between the trolley wheels, and have secured thereto a slotted plate f, to serve as a guide to the incoming and outgoing load C. Parallel with the trolley wheel plate a, and at 105 about one half of the length of the depending plates b, c, d, e, is a cross plate g, fixed to the depending plates; while to the lower portions of each pair of adjacent inner and outer depending plates, b, c, and d, e, are 110

two guide plates *h* having correspondingly beveled edges *i* leading up to the adjacent edges of the guide slot plate *f*. To strengthen further the frame, and particularly to resist the impact of the incoming load against the beveled edge of the guide plates *h*, two braces *j*, diagonally connect the intersecting plates *b*, *g* and *c*, *h*, and *g*, *e*, and *d*, *h*. A tail portion *k* of the guide plate *h*, 10 opposite to the beveled edge *i*, extends outwardly beyond the outer depending plate *b*. It is to be understood that all these members are rigidly secured together by suitable means, as bolts, rivets, and the like.

15 A pair of gripping jaws *G* is hinged to a block fixed between the trolley wheel plates *a*, of the frame, and straddles the trolley rope, each jaw being provided with an outwardly extending lever arm *H*. To move 20 these lever arms, and hence the jaws, simultaneously into and out of gripping engagement with the trolley rope, there is a grip bar *1*, made up of a pair of duplicate pieces *2*, in parallel arrangement, and rigidly secured together by a pivot *3* passing through them and the depending plates *b*, and secured by nuts; by a rod *4*, through their opposite end portion, and nuts; and by a similar rod *5* which forms a bearing for two 25 gripping sheaves, one *6*, a hoisting fall sheave, and the other *7*, an opening fall sheave. This latter rod *5* extends through, and out from, the sides of the grip bar *1*, see Figs. 2 and 3, and has journaled surfaces for two collars *8*, provided with ears *9*. To adjustably connect each one of these collars with its adjacent lever arm *H* of the gripping jaws *G*, two screw members *10*, having opposite screw threads and a nut *11*, 30 are used; one end portion of one member being bifurcated to be secured to its respective lever by a pin *12*, and the corresponding end of the other member being secured between the ears of its respective collar, by a similar pin *13*. The gripping jaws *G* are thus operatively connected to the grip bar *1*; the upward movement of which opens the jaws and unlocks the carrier from the trolley rope; and the downward movement of which, closes the jaws and locks the carrier to the trolley rope. Over the hoisting sheave *6* runs a hoisting fall *J*; while leading over the opening sheave *7* is an 45 opening fall *K*. When the load is borne by either the hoisting fall, or the opening fall, or by both, the load acting downward, closes the jaws, and the carrier becomes locked to the trolley rope.

50 So much of the apparatus as has above 60 been shown and described, embodies the principle of employing the weight of a load to operate gripping mechanism on the carrier, to lock the latter to its support; this principle being disclosed in United States Letters Patent No. 859,542, and issued to

American Cableway Company, assignee, July 9, 1907.

We will now describe the mechanism which controls the grip bar *1*, and hence the jaws *G*, and enables the carrier to remain 70 locked to the trolley rope until the load has found its seat in the carrier; and to become unlocked by the load leaving its seat.

A movable seat or bolt *20*, is pivoted to a link *21*, which is likewise pivoted to a bearing bolt *22* fixed in the longitudinal cross plate *g*; this movable seat *20* is also pivoted to a connecting link *23*, pivotally connected to the free end portion of the grip bar *1*. One end portion of the seat normally lies 80 across the load guide slot *f*; its under part being beveled upward to receive the thrust of the incoming load, and its upper part being hollowed, as at *25*, to receive and support the load. A spring *26*, Fig. 1, connected to the frame and the seat, tends to hold the seat in its normal position; a pin 85 *27* limiting the forward movement of the seat.

That the load may escape from its seat 90 and the carrier, releasing means operated by the moving load are used. A releasing tongue *30*, Figs. 1, 6, 7, 8, is pivoted to the members *d*, by bolt *31*; the free arm of said tongue extends across the load slot *f*, while 95 its other arm is connected by a link *34* to an arm *35* of a throwing lever *36*, which is pivoted to the diagonal braces *j*, and has its other and depending arm in sliding engagement with the pin *27* in the bolt seat. The 100 positions of the pivots of these levers, and their lengths, and proportions are such that the extreme downward movement of the releasing tongue will cause the seat to move back and away from the load slot, and permit the load to pass down by the seat, and thus escape from the carrier, all of which will be made plain hereinafter.

To carry out our invention, any load may 110 be used, provided it has suitable means to engage and operate the seat. The form of load used by us is that of a grab-bucket described and claimed in United States Letters Patent, for improvements in grab-buckets, No. 882,666, issued March 24, 1908, 115 to Clark Chase, one of the present joint inventors; hence we have illustrated that form.

A cross bar *50* connects the sides of the bail of the bucket, and is designed to engage the beveled edge *24* of the seat or bolt *20*, 120 enter the load slot, rest in the seat, and operate the releasing tongue *30*. The hoisting fall *J* passes through a hole in this bar *50*, and is secured to the closing sheave *L* in the grab-bucket.

The opening fall *K*, after passing over the opening sheaves *7*, passes over the guide pulley *N*, and then becomes connected to the grab-bucket by a spreader or rod *O*, the ends 130 of which, by ropes, are connected to opposite

sides of the head M of the bucket; so as to prevent the grab-bucket from twisting, and to keep the cross bar 50 of the bucket, in the plane of the load guide slot f, and allow it 5 freely to enter the slot. Should the opening fall K be held taut, and the hoisting fall J slackened, the grab-bucket would open; and, vice versa, should the opening fall K be loosened, and the hoisting fall J tightened, 10 the grab-bucket would close. But whether the bucket may be prevented from twisting, or may be opened and closed, are immaterial facts in so far as our invention is concerned; all of which will be even more evident when 15 Fig. 8 of the drawings is considered herein-after.

The operation of the carrier B and the load C, here shown as a grab-bucket, may be described as follows: They may be assumed 20 to be in the position shown in Fig. 1. The load C is suspended below the carrier, by the hoisting fall J, which, through its sheave 6, is acting on the gripping arms H and jaws G. The latter grip the trolley rope A, and 25 the carrier is locked fast to the trolley rope. As long as the load is sustained by the hoisting fall, just so long will the carrier be locked to the trolley rope, regardless of whether the hoisting fall is moving or is stationary, or of what the relative positions of 30 the carrier and the load, are. We will next assume that the load is to become removably fastened to the carrier, as it is shown in dotted lines in Fig. 5. The hoisting fall J, and 35 hence the load or grab-bucket C, is raised by suitable means—as a drum engine, not shown—and as it rises, the cross bar 50 of the bail of the bucket, is guided by the beveled edges i of the guide plates h, Fig. 4, 40 into the slot, where it engages the beveled edge 24 of the movable seat 20, which normally lies across the guide slot. As the cross bar continues its upward movement, the hook is forced back out of the path of the ascending 45 cross bar, and assumes the position, indicated in dotted lines in Fig. 4, and permitted by the pivoted link 21, and the connecting link 23. After the cross bar has passed up by the end of the seat 20, the upward movement 50 of the fall is stopped, and the seat and links tend, of their own weight, to return to normal position across the guide slot; but to insure its return, the spring 26, only one end of which is indicated in Fig. 4, contributes 55 its energy to bring about the movement of the seat. The load still being borne by the hoisting fall, the carrier remains locked to the trolley rope. The next step is to lower the cross bar 50, of the grab-bucket into the 60 seat. The hoisting fall J is lowered, and as it descends, the cross bar contacts its seat, as is shown in full lines in Fig. 5. The seat being pivotally connected to the link 21, which is also pivoted to the frame of the carrier, 65 the weight of the load, acting through the

cross bar, moves the forward portion of the seat downward about the pivotal connection with the link 21, and the rear portion upward, this downward movement being arrested by a stop 37. The connecting link 23, 70 and grip bar 1, are thus moved upward until the seat engages the stop 37; but this upward movement of the bar operates the gripping jaws and causes them to release the trolley, and free the carrier so that it may 75 be moved along the trolley; but the release of the jaws does not take place until after the cross bar 50 of the bucket is in its seat, as is shown in full lines in Fig. 5, and the operator has allowed the hoisting fall, and 80 hence the cross bar, to descend enough to move the seat into the position shown in dotted lines in Fig. 5, at which time the load ceases to be borne by the hoisting fall J, 85 shown in dotted lines, and is supported by the seat. In fine, there is no time during the operation of securing the load to the carrier, that the load is not under the control of the operating hoisting fall J; and consequently the objectionable "drop," found in carriers 90 which may be unlocked from the trolley rope when the cross bar of the bucket is above, but not in, its hook, is obviated. The carrier now being free from locking engagement with the trolley rope, may be moved along 95 the trolley by the hoisting fall J in one direction, or by the opening fall K—shown in Fig. 1, but not in Fig. 5, to avoid confusion—in the opposite direction.

To allow the load to escape from the carrier, the opening fall K, Fig. 1, or the rope P, Fig. 8, is held stationary, in relation to the hoisting fall J. The load, and hence the cross bar 50 of the grab-bucket, is lifted out of the position shown in dotted lines in 100 Fig. 5, but the moment it ascends, the weight of the load acts on the hoisting gripping sheave 6, and just as fast as the hoisting fall J moves up, the weight of the load, acting through the sheave grip bar 1, connecting link 23, and seat 20, causes the seat to follow up under the cross bar; and when the seat has moved up enough, it permits the descending grip bar 1, turning about its pivot 3, and moved downward by reason of 105 the weight of the load, to draw the gripping jaws G into gripping engagement with the trolley rope A, and the carrier becomes firmly locked thereto. But the hoisting fall J continues the upward movement of the 110 cross bar 50, in the guide slot. This bar engages the under side of the releasing-tongue 30, lying in the path of the cross bar, and moves the tongue out of the path, and passes above it, the cross bar being shown in full 115 lines in Fig. 6, in the act of just passing by the free end of the tongue. The moment it passes by, and the link 21, connecting link 23, seat 20, releasing tongue 30, connecting link 34, and throwing lever 36 engaging the 120

pin 27 in the seat, are all in the positions shown in full lines, the action of spring 26 causes said parts to snap back into normal position, which is indicated in dotted lines, Fig. 6. The cross bar of the load, now being above the releasing tongue 30, is allowed to descend, and as it does so, it, as shown in dotted lines, engages the top surface of the releasing tongue, and, pushing the tongue down, finally passes by the end of the releasing tongue, and it and all of the connected parts assume the various positions shown in full lines in Fig. 7; but it will be noticed that the seat has been moved back or out of the path of the descending cross bar, and the load is freed from the carrier, and, after the cross bar has passed by the hook, the spring again causes all of the parts to assume their normal position indicated in dotted lines. The load, represented by the cross bar 50, being free from the carrier, may be raised, lowered, and when in the form of a grab-bucket, may be opened and closed in an obvious and well known manner; the means employed, constituting no part of our invention. The grab-bucket and carrier are now in the position shown in Fig. 1, and the cycle of operations involved in getting the load into its seat in the carrier before the carrier was released from its trolley rope; in releasing the carrier from its trolley rope after the load had found its seat in the carrier; in getting the load out of the carrier, by locking the carrier to the trolley rope before the load got out of its seat in the carrier; and by utilizing the movement of the load to control the removal of the seat from the path of the escaping load or grab-bucket; is completed.

Our invention is shown in Fig. 8 embodied in a carrier not designed to be used with a grab-bucket requiring a dumping rope. A simple hauling rope P is substituted for the dumping rope K, and is made fast to the carrier, as by a hook Q engaging a pin R in the frame c. The bar 60 secured to the hoisting fall J, serves the purpose of the cross bar 50 of the grab-bucket shown in Figs. 1 to 7 inclusive.

It will now be plain that our carrier may be used with any kind of a load provided the hoisting fall has suitable means to control the movable seat and the load releasing mechanism.

Desiring to protect our invention in the broadest manner legally possible, what we claim is:—

1. In a carrier movably mounted upon a support, and provided with gripping mechanism to engage the support, and with a hoisting fall operatively connected to the gripping mechanism, to sustain a load; a seat for the load, operatively connected with the gripping mechanism, the movement of

said seat into position to engage and support said load, being controlled by the moving load.

2. In a carrier movably mounted upon a support, and provided with a gripping mechanism to engage the support, and with a hoisting fall to sustain a load; a movable seat for the load, operatively connected with said gripping mechanism and adapted to be moved by the load to cause the gripping mechanism positively to disengage the support.

3. In a carrier movably mounted upon a support, and provided with gripping mechanism to engage the support, with a hoisting fall to sustain a load, and with a fall to haul and hold the carrier; a movable seat for said load, operatively connected with said gripping mechanism, and adapted to be so controlled by the moving load as to move into position to engage and support said load, but also to be moved by the load to cause the gripping mechanism to disengage the support.

4. In a carrier movably mounted upon a support, and provided with gripping mechanism to grip the support, a hoisting fall to sustain a load, and a hauling fall; a movable seat for said load, operatively connected with said gripping mechanism, and so designed as to permit not only the moving load to move by and above said seat, but also the latter to move into position to support the load; and means controlled by the moving load whereby the seat may be caused not to support the load, and permit the load to escape from the carrier.

5. In a carrier movably mounted upon a support, and provided with gripping mechanism to engage the support; a pivoted bar operatively connected to said mechanism; a sheave mounted in said bar; a hoisting fall to sustain a load, engaging said sheave; a movable seat for the load operatively connected with the pivoted bar adapted to be so controlled by the moving load as to move into position to engage and support said load.

6. In a carrier movably mounted upon a support, and provided with a gripping mechanism to engage the support; a pivoted bar operatively connected to said mechanism; a sheave mounted in said bar; a hoisting fall to sustain a load, engaging said sheave; a movable seat for the load, operatively connected with said pivoted bar, and adapted to be moved by the load to cause the bar to move the gripping mechanism out of engagement with the support.

7. In a carrier movably mounted upon a support, and provided with gripping mechanism to engage the support; a pivoted bar operatively connected to said mechanism; a sheave mounted in said bar; a hoisting fall to sustain a load, engaging said sheave; a

- hauling fall; a movable seat for said load, mounted on two depending links, one of which is connected to the free end of the pivoted bar operatively connected with said
- 5 gripping mechanism, and the other to the frame of the carrier, said seat lying normally in the path of the moving load, and having a beveled edge to be engaged by the incoming load so that the latter may force
- 10 the seat back and pass by and above the seat; all being so designed that the load may be lowered into the seat, the movement of which causes the gripping mechanism to disengage the support.
- 15 8. In a carrier movably mounted upon a support, and provided with gripping mechanism to grip the support; a pivoted bar operatively connected to said mechanism; a sheave mounted in said bar; a hoisting fall
- 20 to sustain a load, engaging said sheave; a hauling fall; a movable seat suspended from two links, one depending from the free end of the pivot bar, and the other from the frame, said seat lying normally
- 25 in the path of the moving load, and having an upwardly inclined beveled edge to be engaged by the incoming load to permit it to pass by; and being so pivoted to the said links that when the load descends into the seat, the connecting link, bar and gripping 30 mechanism are so moved that the latter disengages the support; means lying in the path of the moving load, and operatively connected to the seat, whereby the moving load causes said means to move said seat out 35 of the path of the descending load, and permit it to escape from the carrier.

In testimony whereof each of us affixes our signature in the presence of two witnesses.
